(57) **CLAIM**

The ornamental design for a sonic sensor, as shown and described.

DESCRIPTION

FIG. 1 is a perspective view of a sonic sensor in accordance with the present invention;

FIG. 2 is a front plan view of the sonic sensor of FIG. 1;

FIG. 3 is a left side plan view of the sonic sensor of FIG. 1;

FIG. 4 is a rear plan view of the sonic sensor of FIG. 1;

FIG. 5 is a right side plan view of the sonic sensor of FIG. 1;

FIG. 6 is a top plan view of the sonic sensor of FIG. 1;

FIG. 7 is a bottom plan view of the sonic sensor of FIG. 1;

FIG. 8 is a bottom left side perspective view of the sonic sensor of FIG. 1;

FIG. 9 is a top front perspective view of the sonic sensor of FIG. 1;

FIG. 10 is a rear right side perspective view of the sonic sensor of FIG. 1;

FIG. 11 is a rear left side perspective view of the sonic sensor of FIG. 1; and,

FIG. 12 is a bottom right side perspective view of the sonic sensor of FIG. 1.
